UNITED STATES PATENT OFFICE.

JACOB KERSTEN, OF ALLEGAN, MICHIGAN.

DESIGN FOR A RADIO LOUD SPEAKER.

Application filed May 15, 1926. Serial No. 17,727. Term of patent 7 years.

To all whom it may concern:

Be it known that I, JACOB KERSTEN, a citizen of the United States, residing at the city of Allegan, in the county of Allegan and State of Michigan, have invented a new, original, and ornamental Design for Radio Loud Speaker, of which the following is a specification, reference being had to the accompanying drawing, forming a part thereof.

In the drawing,—

Fig. 1 is a front elevation of a radio loud speaker showing my new design, and
Fig. 2 is a side elevation of the same.

I claim:

The ornamental design for a radio loud speaker, as shown.

JACOB KERSTEN.
